CLAIM

The ornamental design for a tool handle head, as shown and described.

DESCRIPTION

FIG. 1 is a perspective view showing a new design for a tool handle head;

FIG. 2 is a front view thereof, the rear view being a mirror image to the front view;

FIG. 3 is a right side view thereof, the left side view being a mirror image to the right side view;

FIG. 4 is a top view thereof; and,

FIG. 5 is a bottom view thereof.

The broken lines in the drawings are shown for illustrative purposes only and form no part of the claimed design. In addition, the surface shading illustrated in the drawings is provided merely to highlight the contour of design; it is not intended to be illustrative of texture or gloss.
